UNITED STATES PATENT OFFICE.

HENRY LIKLY, OF ROCHESTER, NEW YORK, ASSIGNOR TO HENRY LIKLY & COMPANY,
OF ROCHESTER, NEW YORK, A CORPORATION OF NEW YORK.

TRUNK-DRAWER LOCK.

1,276,233.

Specification of Letters Patent. Patented Aug. 20, 1918.

Application filed March 4, 1918. Serial No. 220,112.

To all whom it may concern:

Be it known that I, HENRY LIKLY, of Rochester, in the county of Monroe and State of New York, have invented certain new and useful Improvements in Trunk-Drawer Locks; and I do hereby declare the following to be a full, clear, and exact description of the same, reference being had to the accompanying drawings, forming a part 10 of this specification, and to the reference-numerals marked thereon.

The invention relates to travelers' trunks and more particularly to wardrobe trunks in which a series of vertically disposed 15 drawers or trays are arranged in the body portion of the trunk and wardrobe hanger supports are disposed in its hinged cover portion, but the invention is adapted for use in trunks having drawers or trays variously 20 disposed therein.

It is obviously desirable to provide means whereby one or more of the drawers or trays in one section of a wardrobe trunk may be securely locked closed when the wardrobe 25 section is unlocked and opened to give free access to the garments therein.

This invention has for its more special object to provide simple, inexpensive and efficient means whereby one of the drawers or 30 trays of the open trunk may be locked closed by the same lock which fastens the closed trunk cover.

The invention also includes an auxiliary latch device whereby the locking of one 35 drawer or tray assures the simultaneous locking of one or more adjacent drawers, or all of the drawers, said auxiliary locking device being also adapted for convenient temporary disposal when not so used, within the trunk 40 wardrobe section to therein serve as a garment hanger if so desired.

To these and other ends the invention consists in certain improvements and combinations of parts, all as will be hereinafter more 45 fully described, the novel features being pointed out in the claims at the end of the specification.

In the drawings:

Figure 1 is a front elevation of a preferred 50 embodiment of the invention showing a fully opened end-supported wardrobe trunk in which all four drawers are locked, and also indicates by dotted lines how the unused auxiliary drawer locking device may be dis-

posed as a clothes hanger in the trunk cover 55 wardrobe section;

Fig. 2 is an enlarged detail sectional plan view showing how the closed wardrobe section may be locked to its drawer section;

Fig. 3 is a still further enlarged detail 60 sectional plan view showing use of the trunk lock with the auxiliary locking device applied as in Fig. 1, for locking the trunk drawers or trays, and

Fig. 4 is an enlarged detail vertical section taken on the line $a-a$ in Fig. 1.

Similar reference characters throughout the several views designate the same parts.

The numeral 1 indicates the drawer or tray-holding section of the trunk and 2 is 70 its wardrobe section which is held by hinges 3 to the drawer section 1. In the section 1 are shown four drawers 4, 5, 6, 7, each having a suitable handle 8 for opening and closing it. Preferably to the front of one of the 75 intermediate drawers, the one 6 as shown, is fixed a catch comprising a face plate 9 preferably carrying a cup 10 within which projects an impressed flange portion 11 of the plate 9, surrounding an opening of this plate 80 into which may pass a lock casing 12 fixed to a hasp 13 pivoted at 14 to a plate 15 fastened to a side wall 16 of the trunk section 1. Two spring actuated latches or lock bolts 17, 17, held in the lock casing 12, are 85 adapted to be pressed inwardly by the plate flange 11 and to pass said flange and then spring outwardly behind it as shown in Fig. 3, to lock the hasp to the drawer 6, and thus prevent opening of said drawer except by 90 an authorized person having a key to be introduced in the hasp keyhole 18 for drawing back the latches 17 to allow backward swinging of the hasp 13 on its hinge pin 14.

The drawer 6 may alone be locked as above 95 described without using the auxiliary latch device, in which case the catch plate 9 may be fixed directly to the front face of the drawer; but when an adjacent drawer 5 is to be locked simultaneously with the locking 100 of the drawer 6, the auxiliary latch device 20 is employed, and to accommodate it, a filling plate 21 is interposed between the catch face plate 9 and the face of the drawer, as shown in Fig. 3. The plates 9, 21, together about 105 equal the thickness of the auxiliary latch device 20 which is preferably formed of a metal rod or heavy wire having a head loop 22,

and two abutting laterally extending stem portions 23, 23, from which extend two limbs 24, 24, the extremities of which are preferably formed into hooks 25, 25. The auxiliary latch loop 22 is adapted to snugly fit around the margins of the affixed plates 9, 21, and one of said latch parts 24 then overlies the face of the drawer 5, so that when the lock hasp 13 of the opened trunk is 10 swung inwardly and overlies the plate 9 and a portion of the auxiliary latch loop 22, as shown in Figs. 1 and 3, and the hasp is engaged by its latches 17, acting behind the plate flange 11, the drawer 6 and also the 15 other drawer 5 in front of which the locking device extends, will be simultaneously locked in the trunk drawer section 1.

The catch 9, 10, applied to drawer 6, as shown in Figs. 1 and 3, is operatively similar to the catch 9, 10, applied to the side wall 26 of the trunk wardrobe section 2, as shown in Figs. 1 and 2, whereby the same lock carrying hasp 13, hinged to the trunk drawer section 1, is available for engaging 25 and securing the catch of the closed trunk wardrobe section 2, or the catch on the drawer 6 in the section 1 of the opened trunk as hereinabove described.

To increase the scope and effectiveness of 30 the auxiliary locking device 20, I provide means coöperating with its opposite ends when it is in operative position for insuring locking of all the trunk drawers 4, 5, 6, 7, simultaneously, and to this end there is located between the meeting edges of the drawers 4 and 5, and of the drawers 6 and 7, a parting strip or rail 27 having a projection 28 extending beyond the plane of the front faces of the drawers, and which is 35 perforated to receive the coacting hook end 25 of the auxiliary locking device, as sufficiently shown in Figs. 1 and 4 of the drawings. In the event that it is desired to provide partitions between the drawers the perforated projections 28 may be formed on or 40 secured to the edges of said partitions, as will be understood. When the auxiliary locking device is in operative position its hook ends 25 lie in the path of the drawers 4 and 7, thus causing all of the drawers to 45 be held in closed position until such time as the auxiliary locking device is detached, which is accomplished by first unlocking the hasp 13 from the catch 9, 10 on the drawer 6, and then swinging the hasp outwardly 50 clear of the drawer, and then disengaging the auxiliary locking device loop 22 from the drawer plates 9, 21, and slipping its opposite end hooks 25 from the perforations 55 of the projections 28 on the drawer parting strips 27.

When the auxiliary locking device 20 is not used for securing the closed trunk drawer or drawers, as above described, it may be temporarily laid aside by engaging 65 its opposite end hooks 25 over any suitable garment hanger support 29, arranged in the top of the trunk wardrobe section 2 and when so disposed the locking device 20 may itself serve as one of said hangers, as sufficiently illustrated by dotted lines in Fig. 1 70 of the drawings.

I claim as my invention:

1. A trunk drawer lock comprising a 75 catch on one of the drawers, and an operatively similar catch on the openable trunk cover, in combination with a hasp lock on one trunk section adapted to lock with either the closed trunk cover catch or the catch on the aforesaid drawer of the opened 80 trunk.

2. A trunk drawer lock comprising a catch on one of the drawers, and an operatively similar catch on the openable trunk cover, in combination with a hasp lock on 85 one trunk section adapted to lock with either the closed trunk cover catch or the catch on the aforesaid drawer of the opened trunk, and an auxiliary latch device applicable to the aforesaid drawer catch and having parts then overlying one or more adjacent drawers, whereby a plurality of trunk drawers may be locked closed simultaneously when the hasp lock is engaged with the first named drawer catch. 90

3. A trunk drawer lock comprising a catch on one of the drawers, and an operatively similar catch on the openable trunk cover, in combination with a hasp lock on one trunk section adapted to lock with 100 either the closed trunk cover catch or the catch on the aforesaid drawer of the opened trunk, and an auxiliary latch device applicable to the aforesaid drawer catch and having parts then overlying one or more adjacent drawers, whereby a plurality of trunk drawers may be locked closed simultaneously when the hasp lock is engaged with the first named drawer catch; said auxiliary 105 drawer latch device having opposite end hooks adapting it for suspension upon hanger supports in the trunk wardrobe section to then serve as a garment hanger. 110

4. In a trunk, the combination of a 115 drawer section having a plurality of drawers supported therein, a wardrobe section hinged to the drawer section, a hasp lock adapted to engage either the wardrobe section or one of said drawers, and means coöperating with said hasp lock for locking all of said drawers. 120

HENRY LIKLY.
